CHRIS SILBER, OF MERIDEN, CONNECTICUT, ASSIGNOR TO THE MERIDEN BRITANNIA COMPANY, OF SAME PLACE.

DESIGN FOR A HANDLE FOR SPOONS, &c.

SPECIFICATION forming part of Design No. 27,452, dated August 3, 1897.

Application filed June 28, 1897. Serial No. 642,757. Term of patent 3½ years.

To all whom it may concern:

Be it known that I, CHRIS SILBER, of Meriden, in the county of New Haven and State of Connecticut, have invented a new Design 5 for the Handles of Spoons, Forks, &c.; and I do hereby declare the following, when taken in connection with the accompanying drawing, and the letters of reference marked thereon, to be a full, clear, and exact description 10 of the same, and which said drawing constitutes part of this specification and represents a face view.

This invention relates to a design for the 15 ornamentation of the handles of spoons, forks, and like articles of table-service; and the design consists in the configuration and ornamentation as shown in the accompanying illustration and hereinafter described.

As herein shown, the handle expands gradually from its inner end outward and upward, 20 its top crowned by reversely-curved scroll ornaments A on opposite sides of a centrally-arranged shell-like tip B. Depending from

the scrolls A on opposite sides and forming a border for the upper portion of the handle are 25 foliated scrolls C, gradually diminishing in width and represented as lying upon a plain panel D. A similar foliated-scroll ornamentation E rises from a point slightly above the center of the handle, forming a border for 30 that portion thereof, and at the inner end of the handle is a small scroll ornamentation F, from which a gradually-diminishing tracery G extends upward for a short distance upon the narrower portion of the handle, all as 35 shown in the accompanying illustration.

I claim—

The design for the handle for spoons, forks &c., as herein shown and described.

In testimony whereof I have signed this 40 specification in the presence of two subscribing witnesses.

CHR. SILBER.
